UNITED STATES PATENT OFFICE

117,518

DESIGN FOR A TABLECLOTH

Bert Elfenbein, Scarsdale, N. Y., assignor to Felix Tausend & Sons, New York, N. Y.

Application July 18, 1939, Serial No. 86,064

Term of patent 3½ years

To all whom it may concern:

Be it known that I, Bert Elfenbein, a citizen of the United States, residing at Scarsdale, county of Westchester, and State of New York, have invented a new, original, and ornamental Design for a Tablecloth, of which the following is a specification, reference being had to the accompanying drawing, forming part thereof, wherein the figure is a face view of a quarter section of the tablecloth showing my new design, the other three sections being identical with that here disclosed, arranged in proper relation to complete the table-cloth.

I claim:

The ornamental design for a tablecloth, substantially as shown and described.

BERT ELFENBEIN.
